FLOODLIGHT OR SIMILAR ARTICLE

Henry R. Hahn, Portland, Conn., assignor to Infranor of
North America, Inc., Berlin, Conn., a corporation of
Connecticut

Filed Dec. 3, 1964, Ser. No. 82,893

Term of patent 14 years

(Cl. D48—20)

FIG. 1

FIG. 2

FIG. 4

FIG. 3

FIG. 5

FIG. 1 is a prespective view of a floodlight or similar article embodying my new design.

FIG. 2 is a rear elevational view of the lighting unit of FIG. 1.

FIG. 3 is a perspective view of the lighting unit of FIG. 1 showing generally the side opposite that from the side shown in FIG. 1.

FIG. 4 is a front elevational view of the lighting unit of FIG. 1.

FIG. 5 is a perspective view of a lighting unit embodying a modified form of my new design.

I claim:

The ornamental design for a floodlight or similar article, substantially as shown.
